PROCESS OF PRODUCING ASSISTANTS IN
THE TEXTILE AND RELATED INDUSTRIES

Fritz Guenther and Karl Saftien, Ludwigshafen-on-the-Rhine, Germany, assignors to I. G. Farbenindustrie Aktiengesellschaft, Frankfort-on-the-Main, Germany

No Drawing. Application January 17, 1935, Serial No. 2,224. In Germany January 26, 1934

15 Claims. (Cl. 280—561)

The present invention relates to new assistants in the textile and related industries especially wetting, cleansing, dispersing and like agents and a process for producing same.

5 We have found that organic compounds which contain in the molecule at least one nitrogen atom, at least two organic radicles directly attached to said nitrogen atom, in which the said nitrogen atom is present in a higher oxidation stage than in "organic ammonia substances" and which contain at least one aliphatic (i. e. open chain aliphatic or cycloaliphatic) radicle with at least 8 carbon atoms, are valuable assistants in the textile and related industries, especially wetting, cleansing, dispersing and like agents. The term "organic ammonia substances" is intended to mean for the purposes of the present invention amines and ammonium compounds containing organic radicles including quaternary ammonium compounds.

20 Wetting, cleansing, dispersing and like agents of the kind defined above can be obtained by treating amines containing at most one hydrogen atom directly attached to nitrogen with oxidizing agents, while taking care that no degradation of the amines but a combination of oxygen on the amino nitrogen atom takes place and introducing at any time an aliphatic radicle with at least 8 carbon atoms. The introduction of the latter may either consist in selecting such amines as already contain such a radicle or, if this is not the case, by reacting the amine before or after the oxidation with a compound capable of introducing an aliphatic radicle of the said kind. If desired, further radicles of any desired kind may be introduced.

25 By carrying out the said oxidation with tertiary amines

45 (in which R₁, R₂ and R₃ stand for organic radicles two of which may be connected with one another) amineoxides are obtained which correspond to the formula

55 If, however, secondary amines R₁—NH—R₂ are oxidized in the said manner amineoxides are obtained which are tautomeric with the correspond-

ing hydroxylamines. These compounds may be represented by the following formulae:

(Amineoxide form) (Hydroxylamine form)

10 Open chain aliphatic or cycloaliphatic radicles suitable for the purposes of the present invention are for example those of lauric, stearic, palmitic, oleic and ricinoleic acids, the hydrocarbon radicles corresponding to the montanic acids, resinic and naphthenic acids and to the alcohols and carboxylic acids obtainable by the oxidation of paraffin wax. Furthermore the term is intended 15 to include radicles of hydrogenated aromatic hydrocarbons of high molecular weight, as for example decahydronaphthalene. The expression "aliphatic radicals" as employed in the claims covers both open chain aliphatic radicals and cyclo-aliphatic radicals and radicals in which 2 open chain radicals are joined together as for example in compounds of the type obtained when a piperidine compound is employed as the amine.

20 In the said wetting, cleansing, dispersing and like agents the said organic radicles containing at least eight carbon atoms are connected to a nitrogen atom either directly or by means of other atoms or atomic groups, such as oxygen atoms or sulphur atoms or carbonyl, carboxylic acid ester, carboxylic acid amide, sulphonate or sulphonamide groups, or of organic rings. The chains of radicles of high molecular weight may also be interrupted by one or more of the said atoms or atomic groups.

25 Secondary and tertiary amines suitable as initial materials are for example octyl propylamine, cetyl butylamine, dodecyl naphthylamine, decyl dimethylamine, dodecyl dimethylamine, hexadecyl diethylamine, oleyl dimethylamine, and amines obtainable by the reaction of primary or secondary amines of low molecular weight with higher molecular halogen-paraffin 30 hydrocarbons. Other suitable amines are N-dimethyldecahydronaphthylamine, N-dodecylethylaniline, N-octylpiperidine, N-dialkylethylenediamines which are acylated on one side by fatty acid radicles of high molecular weight, the dodecyl ether of para-dimethylaminophenol, the dodecyl ester of N-dimethylaminoethyl alcohol, N-monomethyl-C-dodecylaniline, N-dimethyl-C-dodecylaniline and the cetyl amide of dimethylaminoacetic acid. Amines of the said kind which contain any desired substituents, as for example 35 halogen atoms, hydroxy, carboxyl, ester, ether,

55

amide, sulphonic and hydroxyethyl groups, or which contain further primary, secondary or tertiary amino groups may also be employed as initial materials.

- 5 The said amines may be subjected to the oxidizing treatment alone or in admixture with each other. A great variety of oxidizing agents may be employed, as for example hydrogen peroxide, sodium peroxide, permonosulphuric acid, benzoyl peroxide, sodium hypochlorite and oxygen or mixtures containing oxygen or other gas mixtures having an oxidizing action preferably in the presence of oxidizing catalysts, the oxidation is advantageously carried out in aqueous solution or suspension and/or while employing organic solvents or diluents, such as ethyl alcohol, acetone or benzene, at ordinary or elevated temperature, advantageously between 0° and 100° C. or between 20° and 100° C.
- 10 When the resulting oxidation product contains only two organic radicles attached to nitrogen it is advantageous to introduce further organic radicles; this may be effected in known manner by alkylation, arylation or aralkylation. For example the oxidation product of dodecylmethylamine may be converted into an oxidation product of a tertiary amine by treatment with benzyl chloride or an alkyl iodide. The compounds thus obtainable which contain halogen may be converted into the corresponding amine oxides by means of silver oxide; if instead of the alkyl iodides alkyl sulphates are employed, the conversion into the amine oxides may be effected by means of barium hydroxide. If the amines employed as initial materials contain no aliphatic or cycloaliphatic radicles containing at least eight carbon atoms, it is preferable during the conversion of the oxidation product into the oxidation product of a tertiary amine to introduce into the molecule a radicle of high molecular weight. Thus for example the oxidation product of dimethylamine may be converted by reaction with cetyl iodide into an oxidation product of a tertiary amine of high molecular weight.
- 15 Oxidation products of secondary amines of low molecular weight may also be converted by the introduction of organic radicles of low molecular weight into oxidation products of tertiary amines, the latter or oxidation products of tertiary amines of low molecular weight being then directly condensed with corresponding compounds of high molecular weight. In this case it is advantageous for the oxidation products to contain atoms or atomic groups which permit of a subsequent introduction of aliphatic or cycloaliphatic radicles of high molecular weight. For example a secondary amine of low molecular weight may be caused to react with chloracetic acid; then before or after the oxidation an aliphatic radicle of high molecular weight may be introduced into the carboxylic acid group contained in the reaction product, for example by esterification. Furthermore the oxidation product of dimethylglycine may be caused to react for example with 20 dodecylamine.
- 20 Oxidation products of tertiary amines of low molecular weight which contain no reactive atoms or atomic groups in the organic radicles are also suitable for the preparation of the said compounds. In this case the introduction of aliphatic radicles of high molecular weight (R₄) may be effected by adding organic compounds R₄—X (wherein X may be OH or the radicle of any acid such as —Cl, —HSO₄, CH₃COO— and the like) on the amineoxide, the double bond be-

tween the oxygen atom and the nitrogen atom being removed in the said reaction. For example the addition of a high molecular alkylhalide on a tertiary alkylamine oxide proceeds according to the following equation.

Thus the oxidation product of trimethylamine may be converted into a product of the desired kind by reaction with dodecyl iodide.

The introduction of the radicles of high molecular weight or the conversion of secondary amines into tertiary amines and the oxidation may thus be carried out in any desired sequence. It is immaterial in what manner the oxidation products of the amines are prepared. For example the oxidation products of secondary amines obtainable by the action of metallo-organic compounds on nitroparaffin hydrocarbons may be converted into oxidation products of tertiary amines containing radicles of high molecular weight according to this invention. The introduction of further organic radicles, as for example by the action of alkylene oxides or by reaction with diazomethane, into oxidation products of tertiary amines already containing aliphatic radicles of high molecular weight is advantageous in many cases. Frequently organic radicles of low molecular weight in the oxidation products may be replaced with advantage by radicles of high molecular weight, as for example by replacing carbomethoxy groups by carbonamido groups of high molecular weight. Oxidation products of primary and secondary amines substituted by halogen, nitro, sulphonic, carboxylic and amino groups may also be obtained according to this invention by introducing such atoms or atomic groups into the initial materials or subsequently into the reaction products.

The products obtainable according to this invention have a high solubility in neutral and alkaline baths. Their basicity is less as compared with the initial materials so that they may be employed for purposes for which the amines themselves are unsuitable by reason of their strongly basic properties. For the greater part they are, however, still capable of forming water-soluble salts with inorganic or organic acids, and these salts may frequently be employed for the same purposes as the oxidation products themselves. The aqueous solutions of the products have a high stability to acids, alkalies and salts and are furthermore stable to the substances forming the hardness in water.

The products may be employed with great advantage as wetting, washing, cleansing and dispersing agents in the textile, leather, paper and other industries. They are especially suitable as additions to any dyebath in which they frequently effect an increase in the solubility or dispersion of the dyestuff and a thorough dyeing and levelling. Even the undesirable precipitation of calcium salts when employing hard water is to a great extent suppressed by reason of the high protective colloid action of the products. The said products may also be employed with advantage for stripping and after-soaping and for improving the fastness to rubbing of many dyes. They are also suitable as additions to printing pastes and as preserving agents and also as valuable additions to mercerizing and bucking liquors and as softening agents for textile materials.

The said products may also be employed with advantage as substitutes for soaps; in the presence of soaps they prevent the precipitation of calcium soaps to a large extent when using hard water by reason of their high protective colloid action. The products may be employed alone, in admixture with each other or together with other usual wetting, washing, dispersing and like agents, as for example Turkey red oil, sulphuric acid esters of aliphatic alcohols of high molecular weight, true sulphonated acids of aliphatic or aromatic compounds of high molecular weight, as for example reaction products of fatty acids with hydroxyalkyl or aminoalkyl sulphonated acids. They may also be employed in admixture with solvents, such as carbon tetrachloride, cyclohexanol, or benzyl alcohol, or together with salts, as for example Glauber's salt, perborates, water-glass, or with protective colloids, such as glue, gelatine, or dextrine.

The following examples will further illustrate the nature of this invention but the invention is not restricted to these examples. The parts are by weight.

25 *Example 1*

21 parts of dimethyldodecylamine are dissolved in 120 parts of ethyl alcohol and heated for nine hours at about 60° C. after the addition of 60 parts of 6 per cent hydrogen peroxide. A solution, capable of dilution with water to give a clear solution, is obtained from which the oxidation product formed may be isolated in solid form by evaporation.

35 The product dissolves very readily in water; the aqueous solution has, *inter alia*, an excellent wetting, foaming and washing power; it has a practically neutral reaction.

40 *Example 2*

60 parts of 6 percent hydrogen peroxide are added to a solution of 30 parts of cetyl-diethylamide in 350 parts of ethyl alcohol and the whole heated for ten hours at about 60° C. After evaporation of the solution, the oxidation product may be obtained in solid form. It has properties similar to those of the product obtainable according to Example 1.

50 *Example 3*

30 parts of 6 per cent hydrogen peroxide are added to a solution of 92 parts of decyldimethylamine in 600 parts of ethyl alcohol and the whole is heated for several hours to about 60° C.

55 If the solution obtained be diluted with water no formation of a precipitate takes place. By evaporation of the water a product is obtained which has excellent wetting and foaming properties.

60 *Example 4*

12 parts of 30 per cent hydrogen peroxide are added to a solution of 62 parts of octodecylidimethylamine in a mixture of 100 parts of water and 250 parts of ethyl alcohol. After heating the mass for three hours to about 60° C. another 12 parts of hydrogen peroxide are added and the mixture is then heated to about 60° C. until the solution obtained, when diluted with water, remains clear. In the manner described above a product having good cleansing and dispersing properties is obtained. By evaporation of the water the new product may be obtained in an anhydrous form.

75 In an analogous manner octodecylidimethyl-

amine or dodecyldibutylamine or chlorstearyl-dimethylamine (obtainable by adding hydrogen chloride on octodecenyldimethyl amine) can be converted into valuable cleansing and dispersing agents by treating with hydrogen peroxide.

5

Example 5

A mixture of 54 parts of the dodecylamide of dimethylamino acetic acid

$C_{12}H_{25}NH-CO-CH_2-N(CH_3)_2$ 10

100 parts of water, 250 parts of ethyl alcohol and 30 parts of 30 per cent hydrogen peroxide is heated for several hours to about 60° C. In this manner a valuable wetting and cleansing agent is obtained.

15

A product having similar properties can be obtained by treating oleyl-N-diethyl-ethylenediamine

$(C_{17}H_{33}CO-NH-CH_2-CH_2-N(C_2H_5)_2)$ 20

with hydrogen peroxide in the manner described above.

Example 6

40 parts of dodecylmonomethylamine are dissolved in 300 parts of ethyl alcohol, 125 parts of 6 per cent hydrogen peroxide are added and the mixture is heated for about 20 hours at 60° C. The ethyl alcohol and the water are evaporated at ordinary temperature in *vacuo* and methyl-dodecylhydroxylamine is obtained in the form of a slightly yellow colored oil. The product yields strongly foaming emulsions with water and possesses an excellent washing and softening power.

25

The product may be alkylated, for example by means of ethyl bromide, whereby a product is obtained which is also soluble in water and has a good washing and wetting power.

30

Example 7

20 parts of C-dodecyl-N-dimethylaniline are dissolved in 700 parts of ethyl alcohol and the solution obtained is heated with 40 parts of 15 per cent hydrogen peroxide so that it boils slightly until a sample is clearly soluble in water. The ethyl alcohol and the water are evaporated in *vacuo*. The amine-oxide formed is water-soluble and possesses an excellent washing, wetting and foaming power.

45

Example 8

70 parts of cyclohexylmethyldodecylamine are dissolved in 350 parts of ethyl alcohol, 150 parts of 6 per cent hydrogen peroxide are added and the mixture is warmed for about 10 hours at 60° C. After evaporating the solvent a clearly water-soluble product of excellent washing, wetting and foaming power is obtained.

50

Example 9

60 parts of a mixture of tertiary amines each of which corresponds to the formula

wherein the radicle $-(CH_2)_x-CH_3$ is a radicle of one of the alcohols corresponding to the fatty acids of palm kernel oil are introduced into 550 parts of an aqueous solution of permonosulphuric acid containing 4.4 parts of active oxygen, the addition being effected slowly while cooling with ice and shaking. The reaction product is allowed to stand for some hours in the cold and then ren-

70

75

dered distinctly alkaline whereby the amineoxide is separated out. The product is filtered off. If desired, it may be redissolved in water, shaken with diethylether in order to remove unconverted 5 amine and dried in vacuo at from 60° to 70° C. It has similar properties as the product obtained according to Example 1.

Example 10

10 24 parts of dodecyl-dimethylamineoxide and 30 parts of methyl iodide are dissolved in 20 parts of ethyl alcohol and the solution is allowed to stand in a closed vessel for about 48 hours. The solvent and non-reacted methyl iodide are 15 distilled off and a yellow crystalline powder is obtained which is readily soluble in water and possesses an excellent foaming, wetting and washing power.

20 A valuable product is also obtained by oxidizing 20 trimethylamine to trimethylamine oxide and reacting the latter with dodecyl iodide by heating the two components in the presence of methyl alcohol in a closed vessel for about 8 hours at from 100° to 110° C.

25 *Example 11*

22 parts of methyldodecylhydroxylamine (obtainable for example according to Example 6) are 30 heated together with 20 parts of benzyl chloride for 1 hour on a water-bath. Water is added to the reaction product, non-reacted benzyl chloride is removed by shaking with diethyl ether and the remaining aqueous solution is evaporated to dryness. A clearly water-soluble product of high 35 wetting and washing power is obtained.

What we claim is:

1. As assistants in the textile and related industries, compounds corresponding to the general formula:

45 wherein R_1 , R_2 , R_3 and R_4 stand for radicals selected from the group consisting of aliphatic and aromatic radicals, at least one of which radicals contains an aliphatic chain of at least 8 carbon atoms.

50 2. The process for producing assistants in the textile and related industries, which comprises treating an amine containing at least one aliphatic radicle with at least 8 carbon atoms and at most one hydrogen atom directly attached to 55 nitrogen with an oxidizing agent at a temperature between about 0° and about 100° C.

3. Assistants in the textile and related industries essentially comprising nitrogenous compounds containing oxygen directly attached to 60 nitrogen selected from the class consisting of compounds corresponding to the general formulae:

wherein R_1 stands for a member selected from the group consisting of hydrogen and aliphatic and aromatic radicals, R_2 and R_3 stand for radicals selected from the group consisting of aliphatic and aromatic radicals, at least one of said radicals containing an aliphatic chain of at least 8 carbon atoms.

4. The process for the production of tertiary 75 amine oxides which comprises reacting with hy-

drogen peroxide a tertiary amine having the formula

5

in which R_1 is one of the group consisting of a straight-chain alkyl radical of more than 7 carbon atoms and mono-alkylated-aryl radical of the benzene series in which the alkyl portion is a straight chain radical of more than 7 carbon atoms, and R_2 and R_3 are both one of the group consisting of a lower alkyl and, jointly, a cyclic polymethylene group.

5. A tertiary amine oxide having the formula

20

in which R_1 is one of the group consisting of a straight-chain alkyl radical of more than 7 carbon atoms and mono alkylated-aryl radicals of the benzene series in which the alkyl portion is a straight chain radical of more than 7 carbon atoms, and R_2 and R_3 are both one of the group consisting of a lower alkyl and, jointly, a cyclic polymethylene group.

6. The compound

30

wherein R is an alkyl straight chain radical of more than 7 carbon atoms and R_4 and R_5 are lower alkyl straight-chain radicals.

7. The dodecylmethylamine-oxide of the formula

40

which product has a fatty aspect, and is a semi-solid mass soluble in water, both in the presence of acids and alkalies, and in organic solvents and lipoids, and whose dilute aqueous solution possesses excellent properties of capillary activity.

8. Process for the manufacture of oxides of tertiary amines, consisting in reacting with oxidizing agents containing the $-O-O-$ group tertiary amines of the general formula:

55

wherein R_1 represents a radical linked to the N-atom through carbon and containing an aliphatic chain consisting of at least 6 carbon atoms, R_2 and R_3 each represent alkyl radicals of low molecular weight the number of carbon atoms of which does not exceed 6.

9. Process for the manufacture of oxides of tertiary amines, consisting in reacting with oxidizing agents containing the $-O-O-$ group tertiary amines of the general formula:

60

wherein R_1 represents a radical linked to the N-atom through carbon and containing a straight aliphatic chain having at least 10 carbon atoms, which chain is not directly linked to the nitrogen

75

atom, R₂ and R₃ each represent methyl radicals.

10. Process for the manufacture of oxides of tertiary amines, consisting in reacting with oxidizing agents containing the —O—O-group tertiary amines of the general formula:

10 wherein R₁ represents a radical linked to the N-atom through carbon and containing nitrogen and a straight aliphatic chain having at least 10 carbon atoms, which chain is not directly linked to the nitrogen atom N, R₂ and R₃ each represent methyl radicals.

11. Process for the manufacture of an oxide of a tertiary amine, consisting in reacting stearoyl-diethylethylene-diamine with Caro's acid.

12. The oxides of tertiary amines of the general formula:

25 wherein R₁ represents a radical linked to the N-atom through carbon and containing an aliphatic chain consisting of at least 6 carbon atoms, R₂ and R₃ each represent alkyls of low molecular weight the number of carbon atoms of which does not exceed 6, which products have a fatty aspect, and are liquid to semi-solid and solid masses 35 soluble in water, both in the presence of acids and alkalies, and in organic solvents and lipoids, and whose dilute aqueous solutions possess excellent properties of capillary activity.

13. The process for the production of tertiary 40 amine oxides which comprises reacting with an

oxidizing agent containing the —O—O-group a tertiary amine having the formula

in which R is an organic hydrocarbon radical containing an alkyl radical having more than 7 carbon atoms, and R₂ and R₃ are both one of the group consisting of a lower alkyl and, jointly, a 10 cyclic polymethylene group.

14. A tertiary amine oxide having the formula

15

in which R₁ is an organic hydrocarbon radical containing an alkyl radical having more than 7 carbon atoms and R₂ and R₃ are both one of the group consisting of a lower alkyl and, jointly, a 20 cyclic polymethylene group.

15. The process for the production of tertiary amine oxides which comprises reacting with an oxidizing agent containing the —O—O-group a tertiary amine having the formula

25

in which R₁ is one of the group consisting of straight-chain alkyl radicals having more than 7 carbon atoms and mono-alkylated-aryl radicals of the benzene series in which the alkyl portion is a straight chain radical of more than 7 carbon atoms, and R₂ and R₃ are both one of the group consisting of a lower alkyl and, jointly, a cyclic polymethylene group.
